(57) CLAIM

The ornamental design for a two part clip, as shown and described.

DESCRIPTION

FIG. 1 is a first top perspective view of the two part clip showing my new design;

FIG. 2 is a second top perspective view thereof;

FIG. 3 is an end view thereof;

FIG. 4 is a top view thereof;

FIG. 5 is a bottom view thereof;

FIG. 6 is a right side view thereof; and,

FIG. 7 is a left side thereof.

The broken lines in the drawings represent environmental structure and form no part of the claimed design.
